[57] CLAIM

The ornamental design for a hand reel, as shown and described.

DESCRIPTION

FIG. 1 is a front perspective view of a hand reel showing my new design;

FIG. 2 is a rear perspective view thereof;

FIG. 3 is a front elevational view thereof;

FIG. 4 is a rear elevational view thereof;

FIG. 5 is a left side elevational view with the opposite side being a mirror image thereof;

FIG. 6 is an enlarged partial section taken along line 6—6 of FIG. 3;

FIG. 7 is an enlarged partial section taken along line 6—6 of FIG. 3 with the handle removed;

FIG. 8 is a front perspective view of a second embodiment of the design shown in FIG. 1;

FIG. 9 is a rear perspective view thereof;

FIG. 10 is a front elevational view thereof;

FIG. 11 is a rear elevational view thereof;

FIG. 12 is a left side elevational view with the opposite side being a mirror image thereof;

FIG. 13 is an enlarged partial section taken along line 7—7 of FIG. 10;

FIG. 14 is an enlarged partial section taken along line 7—7 of FIG. 10 with the handle removed.
